(57) **CLAIM**

The ornamental design for a handle for portable container, as shown and described.

DESCRIPTION

FIG. 1 is a rear perspective view of the handle for portable container removably mounted onto a portable container, such as a paint pail;

FIG. 2 is a front perspective view thereof;

FIG. 3 is a rear perspective view of the handle for portable container shown in FIG. 1;

FIG. 4 is a front perspective view thereof;

FIG. 5 is a rear elevational view thereof;

FIG. 6 is a front elevational view thereof;

FIG. 7 is a left side elevational view thereof, a right side elevational view not being shown as it is a mirror image of the left side elevational view;

FIG. 8 is a top view thereof;

FIG. 9 is a bottom view thereof;

FIG. 10 is a front perspective view of an alternate embodiment of the handle for portable container;

FIG. 11 is a front perspective view of a second alternate embodiment of the handle for portable container;

FIG. 12 is a front perspective view of a third alternate embodiment of the handle for portable container; and,

FIG. 13 is a rear perspective view of a fourth alternate embodiment of the handle for portable container.

The portions shown in dashed lines form no part of the design.
